JOHNSON, OF HOLLYWOOD, CALIFORNIA

RUG AND METHOD OF MAKING THE SAME

Application filed April 2, 1928. Serial No. 266,710.

This invention relates to fabrics and the method of making the same, and is more particularly related to a rug, draperies, pillow cover or like articles which are formed 5 of strips of tape secured intermediate their width to a back with the edges of the strips frayed to form a thread nap.

Rag rugs have heretofore been formed but the manner of forming these rag rugs has 10 for the most part been limited to the braiding of the rags and the securing of the braids together and, in some cases, to a back or mat. Many different forms of artistic designs have been made of these braided rag 15 rugs which, however, do not present frayed or raw edges of the cloth to form a nap similar to that obtained by the weaving of a carpet of yarn or the like. The rag rugs formed of braided rags are not particularly soft.

20 It is, therefore, an object of this invention to provide a rug formed of strips of cloth cut on a bias and secured intermediate their width to a back and having their edges frayed to provide a thread nap of the raw 25 edges of the cloth.

Another object of this invention is to provide a method of forming rag rugs of strips of cloth cut on a bias which includes the securing of the strips of cloth intermediate their 30 width closely together on a back or mat and abrading or fraying the edges of the strips to form a thread nap.

Another object of this invention is to provide a rug of the rag type including a plurality of strips of cloth cut on the bias, the strips of cloth being of alternately different colors and one strip of cloth of each color being secured together and to a back or mat 35 by means of the same securing means and at the same point on the mat, the said strips of cloth having their edges frayed to provide a thread nap of the raw frayed edges of said strips.

40 Other objects and advantages of this invention, it is believed, will be apparent from the following detailed description of a preferred embodiment thereof, as illustrated in the accompanying drawings.

45 In the drawings:

Figure 1 is a top view of a rug embodying this invention.

Figure 2 is a sectional edge elevation thereof on an enlarged scale.

Figure 3 is an enlarged fragmental view 55 in edge sectional elevation of a rug embodying this invention illustrating the manner of forming the designs in accordance with this invention with two strips of cloth secured to a back at a common point.

Figure 4 is a fragmental view of a strip 60 of bias tape detached from the rug and illustrating the frayed edges thereof.

I have found that a rug of extremely pleasing appearance may be formed of strips of cloth or tape cut on a bias and secured intermediate their width to a mat and having 65 their edges frayed or abraded to provide a thread nap of the loose threads thereby formed on the edges of said strips. I have 70 also found that a very pleasing rug design may be formed by this method when two or more strips of cloth cut on a bias and of different colors are secured to the back at the same point by the same securing means and 75 having their edges frayed so that the loose threads at the edges of said strips of cloth of different colors are intermingled by the abrading or fraying of the edges of the cloth 80 in order to blend said colors together.

In the preferred embodiment of this invention illustrated in the accompanying drawings, 1 indicates a back which may be formed of any suitable or desirable material such, for example, as a heavy cloth which is 85 commonly employed in the construction of rugs having thread nap or surface material secured to a back. Strips of bias tape 2 and 3 are secured to the back 1 by stitching 4. The strips 2 and 3 may be of the same material and it is preferable that two or more 90 of such strips be secured to the back 1 at a common stitching 4. In order to obtain pleasing designs in the construction of the rug, it is preferable that the two strips 2 and 3 which are secured to the back 1 at the common stitching 4 be of different colors. The strips 2 and 3 are secured to the back 1 95 at the stitching 4 intermediate their width with their edges projecting vertically from 100

the back 1. In forming the entire rug, the strips 2 and 3 are secured to the back 1 in close proximity at the stitchings 4, the distance apart of said strips 2 and 3 determining the weight of the rug formed and the character of the nap surface of the rug formed by the loose frayed edges 5 and 6 of the strips 2 and 3, respectively.

After the strips 2 and 3 have been secured to the back 1, it is preferable that a form of abrading device such, for example, as a revolving wheel having a roughened surface be applied to the surface of the rug to engage the edges 5 and 6 of said strips to fray said edges or abrading the same to free the threads at the edges of the strips and to intermingle the threads of the different strips 2 and 3 in order to blend together the colors thereof.

20 In forming the rug in accordance with this invention, it is preferable that the strips 2 and 3 be secured to the back 1 spirally as will be apparent from Figure 1 in order that the most pleasing design be obtained. However, it will be obvious that any other suitable form of design or manner of securing the strips 2 and 3 to the back 1 could be employed, if desired.

Having fully described my invention, it 30 is to be understood that I do not wish to be limited to the details herein set forth, but my invention is of the full scope of the appended claims.

I claim:

35 1. A fabric including a back, a plurality of strips of cloth secured adjacent each other to said back intermediate their width, said strips having their edges extending upwardly from said back and frayed.

40 2. A fabric including a back, and a plurality of strips of bias cloth secured longitudinally to said back with their edges extending upwardly.

3. A rug including a back, a multiplicity 45 of strips of bias cloth tape secured at seams extending longitudinally of said strips, and having their edges extending upwardly from said back and frayed.

4. A rug including a back, a multiplicity of adjacent strips of material secured to said back, and securing means extending longitudinally of said strips, the edges of said strips extending upwardly from the back, and frayed to provide a loose nap surface.

55 5. A rug including a back, a multiplicity of adjacent strips of material secured to said back in close juxtaposition and arranged spirally, securing means extending longitudinally of said strips, the edges of said strips extending upwardly from the back and frayed to provide a loose nap surface.

Signed at Los Angeles, California, this 19th day of March, 1928.

GERTRUDE BELCHER.
